UNITED STATES PATENT OFFICE.

CHARLES HENRY COLE, OF PUEBLO, COLORADO.

SECTIONAL CYLINDER AIR-JACK.

1,031,528.

Specification of Letters Patent.

Patented July 2, 1912.

Application filed June 19, 1911. Serial No. 634,189.

To all whom it may concern:

Be it known that I, CHARLES H. COLE, of Pueblo, in the county of Pueblo and State of Colorado, have invented certain new and useful Improvements in Sectional Cylinder Air-Jacks, of which the following is a specification.

This invention relates to fluid actuated lifting jacks, and it has particular reference to that class of fluid actuated lifting jacks in which a plurality of cylinders are arranged tandem, each cylinder being equipped with a piston which is mounted on a piston stem which is common to all the cylinders.

The present invention has for its object to simplify and improve the type of lifting jacks to which reference is made above, a particular object being to produce a lifting jack which is mainly built up of units of similar construction, thus economizing in the manufacture and enabling repairs to be made when necessary at small expense.

With these and other ends in view, which will readily appear as the nature of the invention is better understood, the same consists in the improved construction and novel arrangement and combination of parts which will be hereinafter fully described and particularly pointed out in the claims.

In the accompanying drawing has been illustrated a simple and preferred form of the invention, it being, however, understood that no limitation is necessarily made to the precise structural details therein exhibited, but that changes, alterations and modifications within the scope of the claims may be resorted to when desired.

In the drawing the single figure represents a vertical sectional view of a fluid actuated lifting jack constructed in accordance with the invention.

The improved implement may be made up of any desired number of cylinder units 1 which are of similar construction and dimensions, said cylinder units being externally threaded at both ends, and each unit being provided near its upper end with a vent aperture 4. The several units are connected together by means of internally threaded bands or collars 8. The lowermost unit is threaded into a base 6, and the topmost unit is provided with a cap or head 7 having a central aperture for the passage of the piston stem 2. The meeting ends of the cylinder units abut upon diaphragms 12 which are centrally apertured for the pas-

sage of the piston stem, which latter is turned or otherwise constructed to present a series of cylindrical sections of gradually reduced diameter, as shown at a, a', a'', a''' , 60 the topmost section operating through the cap 7, while the sections a', a'' and a''' operate through the diaphragms 12. Adjacent to the lower end of each section a, a', a'', a''' is formed a shoulder or offset 20 65 to form a seat for a piston head 3 which is provided with a packing disk 16 interiorly engaging the cylinder unit and with a plate or washer 18, whereby said packing disk is compressed against the piston head, said 70 disk and washer being retained by means of a nut 13 for the reception of which the piston stem is provided with a threaded portion 14. Each of the diaphragms 12 is provided with suitably arranged packing 5 engaging that portion of the piston stem 75 which operates therethrough.

Connected with each of the cylinder units near the lower end thereof is a feed pipe 9, the several feed pipes being connected in 80 series by a stand pipe 21 having at its upper end a relief valve 15. The lowermost inlet pipe has an inlet valve 17, and it is connected by means of a flexible duct 10 with a source of supply, not shown, of fluid pressure. When the improved lifting jack is used for railroad work, it may be operated by compressed air supplied from the train pipe; the device may also be operated by steam under pressure supplied from any 85 convenient source.

The piston stem is provided at its upper end with a serrated cap piece 11 adapted to engage the object that is to be raised or lifted.

In the operation of this device, when the valve 15 is closed, fluid under pressure may be admitted at the valve 17, said fluid being distributed through the inlet pipe 9 and stand pipe 21 to the several cylinder units 100 beneath the pistons which are thereby impelled to rise, the vent openings 4 serving to relieve any pressure above the pistons. By providing a plurality of pistons, as herein shown, a relatively great area is subjected 105 to the fluid pressure which may thus be very effectively utilized for the purpose of raising heavy weights. To restore the pistons to their initial position, the supply valve 17 is closed, and the pressure may now be gradually relieved at the valve 15, permitting the pistons and the stem to settle by gravity.

Having thus described the invention, what is claimed as new, is:—

1. In a fluid actuated lifting jack of the character described, a plurality of similar cylinder units having threaded ends, diaphragms arranged between the meeting ends of the several units, threaded connecting collars engaging the meeting ends of the several units, a base into which the lowermost unit is threaded, a cap threaded upon the uppermost unit, a piston stem operating through said cap and through the several diaphragms separating the cylinder units, pistons mounted upon the stem, one piston being disposed within each cylinder unit, and means for supplying fluid under pressure to each cylinder unit beneath the piston operating therein.
2. In a fluid actuated lifting jack, a plurality of similar cylinder units arranged tandem in vertical series, a base plate associated with the lowermost unit, a head on

the uppermost unit, diaphragms interposed between the several units, a piston stem operating through the head and through the several diaphragms, said stem comprising a plurality of sections of gradually reduced diameter, each section having a shoulder and a threaded portion at its lower end, pistons fitted on the sections of the stem within the several cylinders, said pistons abutting upon the shouldered portions of said sections, nuts on the threaded portions of the piston stem, packing disks and washers interposed between the nuts and the pistons, inlet pipes connected with the cylinder units near the lower ends thereof, a stand pipe connecting the several inlet pipes and having a relief valve at its upper end, and an inlet valve on the lowermost inlet pipe.

CHARLES HENRY COLE.
